APPARATUS FOR FEEDING AND ALIGNING SHEET MATERIAL

Application filed January 23, 1931. Serial No. 510,690.

My invention relates to feeding and aligning sheet material, as for the purpose of presenting it properly to trimming and cutting saws, and the like. The invention is especially advantageous for dealing with insulation building board, homogeneous hardwood board, paper, wood, and fiber pulp board, veneers, and other such materials; and I have hereinafter described and explained it with special reference to this use. Various advantages that can be realized through the invention will become apparent to those skilled in the art from the description hereinafter.

In the drawings, Fig. I is a plan view of an apparatus conveniently adapted for and embodying the invention.

Fig. II is a fragmentary side elevation of the sheet feeding devices of the machine and associated parts, several parts being in section as indicated by the line and arrows II-II in Fig. I; and

Fig. III is a fragmentary side elevation from the front of Fig. I.

In Fig. I, my feeding and aligning apparatus 4 is shown arranged like a table in front of a trimming and cutting equipment 5, comprising saws 6, 6, 6 driven by individual electric motors 7, 7, 7 and located between suitably driven entrance and exit feed roll devices 8 and 9, which control the sheet S during the action of the saws thereon. My apparatus 4 acts to assure presentation of the sheet S to the entrance feed device 8 in proper definite alignment under all circumstances.

As shown in Fig. I, my feeding and aligning table 4 comprises a stop 10 for the edge of the fiber sheet S, associated with means or devices 11 for sustaining the sheet and feeding it along, and concurrently pushing or pressing it against the stop 10. To minimize friction with the edge of the sheet S, the stop 10 may consist of a series or line of upright rolls or rollers 12, preferably with stop walls 13 between them to prevent the leading corner of the sheet S from catching and "blocking" against a roll 12. The rollers 12 are mounted on vertical axes (studs or spindles) 14 secured to the horizontal flanges of angle bars 15, and project through openings in the vertical flanges of these angle bars, which

vertical flanges form the stop walls 13 between the rollers. The feeding means 11 here shown consists of a multiplicity of rotary discs mounted, at suitable intervals, on a series of feed shafts 16 extending at right angles to the stop 10, and suitably spaced apart. Thus each shaft 16 with its discs 11 in effect constitutes one feed roll: however, the multiplicity of discs 11 presents important advantages over a series of mere ordinary rolls, as will appear hereinafter. As shown in Fig. I, the discs 11 of adjacent shafts 16 are staggered.

As shown in Fig. II, the feed discs 11 are mounted on the shafts 16 between flanges 17, 18 suitably secured to the shafts. Preferably, the discs 11 are of a resiliently yielding material that will adhere well by friction to a fiber sheet S. The material that I prefer for this purpose is sponge rubber such as is used for the cushion backs of rubber stamps: it comes in sheets an inch thick from which the discs 11 can easily be cut. They can be cemented or vulcanized to the flanges 17, 18, or simply clamped between them and held from turning by mere friction.

In order that the sheet S may be pushed or crowded over against the stop 10 as it is moved along the latter, provision is made for a movement of discs 11 toward the stop 10 with the sheet resting on them. For their return movement, these discs 11 are relieved of the sheet S, preferably by allowing it to rest on a different set or group of the discs 11, and this other group may also be moved toward the stop 10 while the sheet is resting on them and the first group are out of contact with the sheet. By such alternate action of a plurality of groups of the discs 11, the sheet S can be continually fed along and also continually crowded or pressed over toward and against the stop 10. As here shown, there are two such alternately active disc groups, each comprising the discs 11 on alternate shafts 16a, 16b. This alternate action may be produced in various ways, as by raising and depressing the shafts 16a, 16b while moving them to and fro, lengthwise, toward and from the stop 10, or by having

the discs 11 eccentric to their axes of rotation, or both.

As shown in Fig. III, the eccentric relation of their axes of rotation is realized by having the discs 11 eccentric to the shafts 16, rather than by mounting the shafts 16 in their bearings 19 to revolve eccentric to their own axes. The alternate action is secured by having the eccentric discs 11 of the two groups differently set,—preferably substantially or approximately 180° apart,—so that the discs of the two groups “rise and fall” in alternation. In other words, successive eccentricities in the general direction of feed of the material are set 180° apart. Thus the sheet S is normally engaged and supported only by the eccentricities 11 of one group, while those of the other group are out of contact with the sheet,—except, of course, for brief periods when the eccentricities of the two groups are at mid-throw together, when the sheet S rests on all of the eccentricities concurrently.

As already intimated, the to and fro movement of the discs 11 toward and from the stop 10 is preferably produced by reciprocating or vibrating the shafts 16 lengthwise, rather than by moving the discs 11 to and fro on the shafts. For this purpose, the bearings 19 of each feed shaft 16 are movably mounted, being pivoted in the forked upper ends of swinging links 20, 21 whose lower ends are pivoted at 22 on the machine frame (Fig. II). This mounting results in a slight up and down movement of the feed shaft 16 as it vibrates lengthwise: i. e., the shaft rises on its movement to the left, toward the stop 10, and is depressed as it recedes to the right, away from the stop. As it travels along, the sheet S rises and falls a distance of about half the throw of the eccentric 11. The feed shafts 16 are driven by corresponding drive shafts 25 journaled in bearings 26 on the frame of the machine. As shown in Figs. II and III, the drive shafts 25 carry sprocket wheels 27 which engage a common sprocket chain 28 extending around sprockets 29, 30 suitably mounted in the machine frame. The sprocket chain 28 may be driven by an electric motor 31 through gearing 32 and a chain and sprocket connection 33 to the shaft 34 of the sprocket 30 (Figs. I and II). Intermediate idle sprockets 35 at suitable intervals sustain the active upper run of the chain 28 in engagement with the drive shaft sprockets 27. Any suitable driving connection 36 may be provided between each drive shaft 25 and its feed shaft 16 to permit longitudinal and up and down movement of the latter, such as a flexible disc joint. As shown in Fig. II, each such joint 36 comprises a drum 37 fast on the drive shaft 25, and a flexible disc 38 marginally connected to the drum 37 and centrally connected to the shaft 16. For this purpose, the outer margin of the disc 38 is clamped between the edge drum

37 and a flanged rim 39 fitting over and secured to the drum, and its central portion is clamped between flanges 40, 41 on the shaft 16. If desired, these connections may also be suitably cemented or vulcanized. The disc 38 may be of any suitable flexible material, such as that preferred for the discs 11, as mentioned above.

The feed shafts 16 may be vibrated longitudinally by any suitable actuating means, preferably on the drive shafts 25. As shown in Fig. III, the cranks 42 on the drive shafts 25 belonging to the respective groups of feed shafts (i. e., the cranks 42 of successive drive shafts 25 in the general direction of feed) are set 180° apart, so that the feed shafts of the respective groups move toward and from the stop in alternation. For this purpose, an eccentric or crank 42 is shown at the end of each drive shaft 25, with a link connection 43 to one arm of a bell-crank lever 44 whose other arm is the swinging link 20 that supports one of the feed shaft bearings 19. The bearings 19 are of a thrust type, so as to compel the shaft 16 to move lengthwise with them, and vice-versa. As shown in Fig. II, the forked upper end of the link 43 is pivoted at 45 to a bearing block 46 on the crank 42, and the forked lower end of the link 43 has a universal joint connection 47 to the forked end of the lever arm 44.

At the front of the table 4 is a feed device for passing the sheet S along the cutting and trimming apparatus 5 while definitely maintaining its alignment, consisting of cooperating pairs of feed discs 50, 50, of the same resiliency character as the discs 11, concentrically mounted on shafts 51, 51. As shown in Figs. I and III, the lower shaft 51 is driven by a sprocket and chain connection 52 to the entrance feed device 8 of the cutting and trimming apparatus 5. The ends of the upper shaft 51 are journaled in blocks 53 in vertical ways 54 on the machine frame, and an adjusting screw 55 serves to vary the pressure between the discs 50, 50 according to the thickness and character of the sheet material S.

The revolving discs 11 carry the sheet S along toward the left (Figs. I and III) continuously. The set of eccentricities 11 on which the sheet S rests at any time moves only toward the stop 10. Thus the sheet S is continually pushed over against the stop 10 and brought to a definite alignment with respect to the whole apparatus. After the edge of the sheet S comes in contact with the stop 10, the margins of the discs 11 yield and deflect sidewise, under further thrust against the stop, an amount equivalent to their sidewise movement at each revolution.

Having thus described my invention, I claim:

1. Apparatus of the character described for feeding and aligning sheet material, com-

- prising an aligning stop for the edge of the material, a group of revolving rolls for feeding the material along and pushing it toward said stop, means for vibrating said rolls toward and from said stop, and means for supporting the material out of contact with said rolls during their recession from the stop. 6
2. Apparatus of the character described for feeding and aligning sheet material, comprising an aligning stop for the edge of the material, groups of revolving eccentric rolls for feeding the material along said stop, the rolls of said groups being differently set, so that some of the rolls carry the material 10 while others are out of contact with it, and means for vibrating said groups of rolls in alternation toward and from said stop and concurrently raising and depressing them, rolls moving toward the stop while supporting the material and receding while out of contact with it. 15
3. Apparatus of the character described for feeding and aligning sheet material, comprising an aligning stop for the edge of the material, groups of revolving eccentric rolls for feeding the material along said stop, the rolls of said groups being differently set, so that some of the rolls carry the material while others are out of contact with it, and means 20 for vibrating said groups of rolls in alternation toward and from said stop, rolls moving toward the stop while supporting the material and receding while out of contact with it. 25
4. Apparatus of the character described for feeding and aligning sheet material, comprising an aligning stop for the edge of the material, revolving eccentric rolls for feeding the material along said stop, successive rolls in the general direction of feed of the material being set 180 degrees apart, and means for vibrating the rolls toward and from said stop, the alternate rolls in alternation with the rest, so that rolls move 30 toward the stop while supporting the material and recede while out of contact with it. 45
5. Apparatus of the character described for feeding and aligning sheet material, comprising an aligning stop for the edge of the material, groups of revolving feed shafts with adherent-edged eccentrics for feeding the material along said stop, the eccentrics of said groups being differently set, so that those of one group carry the material while those of another group are out of contact with it, and means for vibrating the groups of feed shafts in alternation toward and from said stop, so that eccentrics move toward the stop while supporting the material and recede while out of contact with it. 55
6. Apparatus of the character described for feeding and aligning sheet material, comprising an aligning stop for the edge of the material; groups of revolving feed shafts with eccentrics for feeding the material along said stop, the feed shafts of said 60 groups alternating and the eccentrics of the respective groups being set 180 degrees apart; drive shafts in line with said feed shafts with actuating connections thereto permitting longitudinal movement of the feed shafts; and cranks on said drive shafts, with actuating connections to said feed shafts to vibrate them lengthwise toward and from said stop, said cranks being set 180 degrees apart on the drive shafts of the two groups of feed shafts, and being co-ordinated with the eccentrics to cause the latter to move toward the stop while supporting the material and to recede while out of contact with it. 70
7. Apparatus of the character described for feeding and aligning sheet material, comprising an aligning stop for the edge of the material, a group of revolving resiliently flexible eccentrics for feeding the material along and pushing it toward said stop, means for vibrating said eccentrics toward and from said stop, and means for supporting the material out of contact with said eccentrics during their recession from the stop. 75
8. Apparatus of the character described for feeding and aligning sheet material, comprising an aligning stop for the edge of the material, groups of revolving resiliently flexible eccentrics for feeding the material along said stop, the eccentrics of said groups being differently set, so that some of the eccentrics carry the material while others are out of contact with it, and means for vibrating said groups of eccentrics in alternation toward and from said stop, eccentrics moving toward the stop while supporting the material and receding while out of contact with it. 80
9. Apparatus of the character described for feeding and aligning sheet material, comprising an aligning stop for the edge of the material, groups of revolving feed shafts with flexible rubber eccentrics for feeding the material along said stop, the eccentrics of said groups being differently set, so that those of one group carry the material while those of another group are out of contact with it, and means for vibrating the groups of feed shafts in alternation toward and from said stop, so that eccentrics move toward the stop while supporting the material and recede while out of contact with it. 105
10. In apparatus of the character described for feeding and aligning sheet material, the combination with an aligning stop for the edge of the material, of revolving feed shafts with eccentric discs thereon resiliently yielding in any axial direction, for feeding the material along and pushing it toward said stop. 115
11. In apparatus of the character described for feeding and aligning sheet material, the combination with an aligning stop for the edge of the material, of revolving feed shafts with eccentric discs of resilient, 120
12. In apparatus of the character described for feeding and aligning sheet material, the combination with an aligning stop for the edge of the material, of revolving feed shafts with eccentric discs of resilient, 125
13. In apparatus of the character described for feeding and aligning sheet material, the combination with an aligning stop for the edge of the material, of revolving feed shafts with eccentric discs of resilient, 130

flexible sponge rubber for feeding the material along and pushing it toward said stop.

12. Apparatus of the character described for feeding and aligning sheet material, comprising an aligning stop for the edge of the material, groups of revolving rolls for feeding the material along said stop, and means for vibrating said groups of rolls in alternation toward and from said stop, and for elevating the rolls moving toward the stop and depressing the receding rolls.

13. Apparatus of the character described for feeding and aligning sheet material, comprising an aligning stop for the edge of the material, revolving rolls for feeding the material along said stop, and means for vibrating the alternate rolls in alternation toward and from said stop, and concurrently raising and depressing them.

14. Apparatus of the character described for feeding and aligning sheet material, comprising an aligning stop for the edge of the material, groups of revolving rolls for feeding the material along said stop, said rolls being mounted for vibration longitudinally toward and from said stop, drive shafts in line with said rolls, flexible sponge rubber disc joints connecting them to the rolls, to permit vibration of the rolls as aforesaid, while driven by the shafts, and cranks on said shafts with actuating connections to said rolls to vibrate them.

15. Apparatus of the character described for feeding and aligning sheet material, comprising an aligning stop for the edge of the material, groups of revolving rolls for feeding the material along said stop, said rolls being mounted for concurrent vibration both longitudinally toward and from said stop and also up and down, drive shafts with connections to said rolls permitting vibration of said rolls as aforesaid while revolving with the drive shafts, and means actuated by the drive shafts for vibrating said groups of rolls as aforesaid, both longitudinally and up and down, in alternation.

16. Apparatus of the character described for feeding and aligning sheet material, comprising an aligning stop for the edge of the material, groups of revolving rolls for feeding the material along said stop, said rolls being mounted for vibration longitudinally toward and from said stop, drive shafts in line with said rolls, flexible disc joints connecting them to the rolls, to permit vibration of the rolls as aforesaid, while driven by the shafts, and cranks on said shafts with actuating connections to said rolls to vibrate them.

17. Apparatus of the character described for feeding and aligning sheet material, comprising an aligning stop for the edge of the material, groups of revolving feed shafts with rubber-edged discs thereon for feeding the material along said stop, bearings for

said shafts and swinging links supporting them for concurrent vibration longitudinally toward and from said stop and up and down, drive shafts for said feed shafts with flexible connections thereto permitting vibration of said feed shafts as aforesaid, and cranks on said drive shafts with actuating connections to said feed shafts to vibrate them, the cranks being set 180 degrees apart on the drive shafts of the two groups of feed shafts.

In testimony whereof, I hereunto sign my name at Trenton, New Jersey, this 19 day of January, 1931.

FRANCIS S. FARLEY.
